(57) **CLAIM**

The ornamental design for a travel mug as shown and described.

DESCRIPTION

FIG. 1 is a front, top, and left perspective view of a travel mug showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a rear, bottom, and right perspective view thereof; and,

FIG. 9 is a perspective view of the travel mug with the lid closed.

The broken lines shown in the drawings represent portions of the travel mug that form no part of the claimed design.

1 Claim, 9 Drawing Sheets
